COVERED PITCHER OR THE LIKE

Tapio Wirkkala, Maamonalahdentie, Lauttasaari, Finland, assignor to Rosenthal - Porzellan Aktiengesellschaft,
Selb, Bavaria, Germany, a corporation of Germany

Filed June 22, 1964, Ser. No. 80,515

Claims priority, application Germany Jan. 22, 1964

Term of patent 14 years

(Cl. D44—21)

I claim:

The ornamental design for a covered pitcher or the like, as shown.
